R. A. McCANN

RAILWAY TRAFFIC CONTROLLING APPARATUS

Filed May 16, 1923

UNITED STATES PATENT OFFICE.

RONALD A. McCANN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed May 16, 1923. Serial No. 639,336.

To all whom it may concern:

Be it known that I, RONALD A. McCANN, a citizen of the United States, residing at Swissvale, in the county of Allegheny and State of Pennsylvania, have invented certain new and useful Improvements in Railway-Traffic-Controlling Apparatus, of which the following is a specification.

My invention relates to railway traffic controlling apparatus, and particularly to apparatus of the type comprising train carried governing means controlled by energy received from the trackway. More particularly, my invention relates to the trackway portion of such apparatus.

I will describe two forms and arrangements of railway traffic controlling apparatus embodying my invention, and will then point out the novel features thereof in claims.

In the accompanying drawings Fig. 1 is a diagrammatic view showing one form of apparatus embodying my invention. Fig. 2 is a view showing one modification of the apparatus shown in Fig. 1 and also embodying my invention.

Similar reference characters refer to similar parts in both views.

Referring first to Fig. 1, the reference characters 1 and 1^a designate the track rails of a railway over which traffic normally moves in the direction indicated by the arrow. These track rails are divided by means of insulated joints 2 into a plurality of successive track sections A—B, B—C, etc. Each such section is provided with a source of track circuit current which comprises, as shown in the drawing, a track transformer designated by the reference character T with an exponent corresponding to the location and having its secondary 7 connected across the rails adjacent the exit end of the section and its primary 8 constantly supplied with alternating current from a generator N over line wires 3. Interposed between each track transformer T and one rail 1 of the associated section is an impedance 9, one function of which is to limit the output of the transformer when its terminals are short circuited by the wheels and axles of a train. Each section is further provided with a track relay designated by the reference character R with an exponent corresponding to the location and provided with two wind-

ings 10 and 11. One winding 10 of each track relay R is constantly connected across the rails adjacent the entrance end of the associated section. Each track section is thus provided with a track circuit which comprises the secondary of a track transformer T, a winding 10 of a track relay R and the two rails of the section in series.

Means are also provided for supplying to the rails in parallel of each section an alternating current which I shall hereinafter term a "local" current. For this purpose each section is provided with an impedance 4 connected across the rails adjacent the entrance end of the section, a similar impedance 6 connected across the rails adjacent the exit end of the section, and a third similar impedance 5 connected across the rails at an intermediate point in the section. The local current for each section is supplied from a local transformer designated by the reference character E with an exponent corresponding to the location, and the primary winding 26 of each local transformer is constantly supplied with alternating current from a line transformer designated by the reference character M with an exponent corresponding to the location. Each such line transformer M is constantly supplied with alternating current over line wires 3 from the generator N.

Referring particularly to section A—B, one local circuit passes from secondary 27 of local transformer E^B, through front point of contact 12 of track relay R^B, wire 13, impedance 6 in section A—B, through both rails in parallel to impedance 4, thence through wire 14, winding 11 of track relay R^A, wire 15, and front point of contact 16 of track relay R^B, to secondary 27 of transformer E^B. This circuit is closed only when track relay R^B is energized. When this relay is de-energized a second local circuit is closed and current flows from secondary 27 of local transformer E^B, through back point of contact 12, wire 15, winding 11 of track relay R^A, wire 14, impedance 4 in section A—B, through both rails in parallel to impedance 5, thence through wire 17 and back point of contact 16 of track relay R^B, to secondary 27 of local transformer E^B. It is therefore plain that the rails of each section are supplied with local current of one relative polarity (which I shall term

"normal relative polarity") from the entrance end to the exit end of the section, or of the other relative polarity (which I shall term "reverse relative polarity") between the entrance end and an intermediate point in the section, depending upon whether the track relay for the section next in advance is energized or de-energized. Under either of these conditions, however, it will be noticed that winding 11 of the track relay for the associated section is included in the local circuit. Each track relay is so designed that for the relay to become energized in such manner as to close its front contacts, both windings 10 and 11 must be energized. It will then be plain that each track relay will be energized only when its associated section is supplied with track circuit current and also with local current.

Located adjacent the entrance end of each section is a signal designated by the reference character S with an exponent corresponding to the location, and each of which signals, in the form here shown, is of the three-position semaphore type capable of indicating "stop," "caution" and "proceed." Each signal is provided with a circuit controller designated by the reference character J with the same exponent as that applied to the signal. Each signal is also provided with a caution circuit which is closed only when the associated track relay is energized. Considering signal S^B, for example, this circuit passes from the secondary winding of transformer M^B, through wire 18, front contact 19 of track relay R^B, wire 20, operating mechanism of signal S^B, and wire 21 back to transformer M^B. Each signal is also provided with a proceed circuit which is closed only when the associated track relay is energized and the signal next in advance indicates proceed or caution. Considering signal S^B, for example, the proceed circuit passes from the secondary of transformer M^C, through wire 23, contact 24 of circuit controller J^C operated by signal S^C, wire 25, front contact 28 of track relay R^B, wire 29, operating mechanism of signal S^B, and wires 21 and 22 back to transformer M^C.

Before explaining the operation of the apparatus it should be understood that the trackway apparatus herein shown and described is capable of co-operation with train-carried governing apparatus in the following manner: When the train occupies a stretch of track which is supplied with track circuit current and with local current of normal relative polarity, the governing apparatus gives a proceed indication on the train; when the train is on a stretch of track which is supplied with local current and also with track circuit current the relative polarity of either of which is reversed, the governing apparatus give a caution indication; and when the train occupies a stretch

of track to which the supply of either local current or track circuit current is for any reason discontinued, the governing apparatus gives a stop indication.

As shown in the drawing, the parts of the apparatus are in normal positions, that is, the positions they occupy when not influenced by the presence of a train or trains. Under these circumstances each track section is supplied throughout its length with track circuit current and with local current of normal relative polarity. All track relays R are, therefore, energized and each of the signals S displays a proceed indication. 80

I will now assume that a train occupies the section to the right of point C. The consequent shunting of winding 10 of track relay R^C causes this relay to become de-energized, thus allowing signal S^C to display a stop indication, thereby opening contact 24 of signal circuit controller J^C. The closing of the back contacts of relay R^C causes local current of reverse relative polarity to be supplied to the rails of section B—C between impedances 4 and 5. Relay R^B is therefore energized and signal S^B displays a caution indication, its proceed circuit having been opened by circuit controller J^C. Local current of normal relative polarity is supplied to section A—B between impedances 4 and 6 and signal S^A is at proceed. The section to the left of point A is supplied with track circuit current and local current of normal relative polarity in a manner similar to section A—B. It is clear that a second train moving in the direction of the arrow will receive a proceed indication until it reaches point B. Between point B and impedance 5 in section B—C, the train will receive a caution indication due to the reversal of the local current in this portion of track. Between impedance 5 and point C, the train will receive a stop indication as a result of the interruption of local current in this portion of track, and this stop indication will continue from point C as far as the train which is occupying the section to the right of C, because of the absence of track circuit current in this portion of track. 100 105 110 115

It will be observed that if for any reason the local circuit of a section is broken so that the supply of local current to that section is interrupted, the associated track relay R is de-energized and the signal controlled thereby is therefore allowed to display a stop indication. This control renders it impossible for a signal to display a proceed or caution indication unless the corresponding local and track circuit currents are being supplied to the section which it governs. Another advantage of this arrangement of apparatus is that if there exists in the rails a foreign local current which tends to coun- 120 125 130

teract the normal local current, and if the magnitude of this foreign current is sufficient to render unreliable the operation of the governing mechanism by reducing the 5 effective local current, this reduction will also operate to de-energize the associated track relay and will thereby place the corresponding signal at stop.

Referring now to Fig. 2, each track relay 10 R comprises only one winding 10, and this winding is constantly connected across the rails adjacent the entrance end of the associated section. Each such relay is responsive to reversals in the relative polarity of the 15 current supplied thereto. The primary 8 of each track transformer T is supplied with alternating current of one relative polarity or the other from the secondary of the associated line transformer M by means of a 20 pole changer designated by the reference character P with an exponent corresponding to the location and operated by the associated signal S. Associated with each section is an auxiliary relay designated by the 25 reference character K with an exponent corresponding to the location and arranged to be energized only when the local circuit for the associated section is complete. Referring, for example, to section A—B, this section 30 is provided with one local circuit which passes from secondary winding 27 of local transformer E^B, through wire 30, contact 35—37 of circuit controller L^B operated by signal S^B, wire 31, impedance 6 of section 35 A—B, through both rails of the section in parallel to impedance 4, wire 32, winding of relay K^A, and wire 33 back to transformer E^B. This circuit is closed when signal S^B is at proceed or caution, under which conditions 40 local current of normal relative polarity is supplied to the rails of section A—B throughout their length. When signal S^B displays a stop indication the closing of contact 35—36 of signal circuit controller L^B completes a second local circuit and current flows from secondary 27 of local transformer E^B through wire 30, contact 35—36 45 of circuit controller L^B operated by signal S^B, wire 34, impedance 5 in section A—B, through both rails in parallel to impedance 4, wire 32, winding of relay K^A, and wire 33, back to transformer E^B, thus supplying local 50 current of reverse relative polarity to that portion of section A—B which lies between impedances 4 and 5. It will be noted that each of these local circuits includes the auxiliary relay K^A.

Each signal S is controlled by the associated track relay R and auxiliary relay K. Referring particularly to section B—C and signal S^B for governing traffic therethrough, when signal S^B indicates caution or proceed, track circuit current of one relative 60 polarity, which I shall term "normal" relative polarity, is supplied to the rails of sec-

tion B—C. Relay R^B is therefore energized in the normal direction and current flows from the secondary of line transformer M^B through wires 36 and 37, front contact 38 of relay K^B, wire 39, normal contact 40 of relay R^B, wire 41, operating mechanism of signal S^B, wire 43, normal contact 44 of relay R^B, wire 45, front contact 46 of relay K^B, and wire 47 back to the secondary of transformer M^B, thus 70 causing signal S^B to display a proceed indication. The caution circuit for signal S^B is also controlled by relay K^B and passes from the secondary of line transformer M^B, through wires 36 and 37, front contact 38 of relay K^B, wire 39, reverse contact 40 of relay R^B, wire 42, operating mechanism of signal S^B, wire 43, reverse contact 44 of track relay R^B, wire 45, front contact 46 of relay K^B, and wire 47 back to the secondary 80 of transformer M^B. This circuit is closed only when relay K^B is energized and relay R^B is energized in the reverse direction under which condition signal S^B displays a caution indication. It is clear that the 90 failure of the local circuit for a section will de-energize the associated relay K and cause the associated signal to display a stop indication.

Trains passing through the stretch of 95 track shown in Fig. 2 are governed in precisely the same manner as explained in connection with Fig. 1, with the single exception that the caution indication is caused in Fig. 2 by reversing the relative polarity of the track circuit current, whereas this is accomplished in Fig. 1 by reversing the relative polarity of the local current.

Although I have herein shown and described only two forms of railway traffic controlling apparatus embodying my invention, it is understood that various changes and modifications may be made therein within the scope of the appended claims without departing from the spirit and scope of my 105 invention.

Having thus described my invention what I claim is:

1. Railway traffic controlling apparatus comprising a section of railway track, a signal for said section for at times displaying a more restrictive indication, means for supplying local current to the rails of said section in parallel, and means for causing said signal to display a less restrictive indication only when such means is operative.

2. In combination, a section of railway track, means for supplying an alternating current to the rails of said section in parallel, a signal for said section, and means for causing said signal to display a restrictive indication when such supply is interrupted.

3. In combination, a section of railway track, a signal for said section responsive

- to traffic conditions in said section, means for supplying an alternating current to the rails of said section in parallel, and means for causing said signal to display a restrictive indication when said supply is interrupted. 11. In combination, a plurality of successive sections of railway track, a relay for each section having two windings, means responsive to traffic conditions in each section for supplying one winding of the associated relay with track circuit current, means controlled by each such relay for supplying local current to the track rails of the section next in rear and to the remaining winding of the relay associated with such section, a signal for each section biased to give a more restrictive indication, and means for causing each such signal to display a less restrictive indication only when both windings of the associated track relay are energized. 70
4. In combination, a section of railway track, a track circuit for said section including the rails of said section in series, 75
- 10 a signal for said section controlled by said track circuit, an auxiliary circuit including the rails of said section in parallel, and means for operating said signal only when said auxiliary circuit is complete. 15 5. In combination, a section of railway track, a source of track circuit current for said section, a track relay for said section, a signal controlled by said track relay, an auxiliary circuit including the rails of said 20 section in parallel, and means for operating said signal only when said auxiliary circuit is complete. 25 6. In combination, a section of railway track, a signal for said section for at times displaying one indication, means for causing said signal to display a different indication when said section is occupied by a train, means for supplying a current to the rails of said section in parallel, and means 30 for causing said signal to display said different indication when such supply is ineffective, irrespective of traffic conditions in said section. 35 7. In combination, a section of railway track, means for supplying the rails of said section with track circuit and also with local current which traverses the rails of the section in parallel, and trackway signaling means controlled jointly by said two 40 currents. 8. In combination, a section of railway track, means for supplying said section with track circuit current, means for supplying the rails of said section in parallel with local current, a relay controlled by said two 45 currents, and signaling means controlled by said relay. 9. In combination, a section of railway track, a local circuit including at least one rail of said section, a track circuit for said section, a relay having two windings one included in each said circuit, and signaling means controlled by said relay. 50 10. In combination, a plurality of successive sections of railway track, a relay for each section having two windings, means responsive to traffic conditions in each section for supplying one winding of the associated relay with track circuit current, means controlled by each such relay for supplying local current to the track rails of the section next in rear, and to the remaining winding of the relay associated with such section, and traffic controlling apparatus controlled 55 by each said relay. 120
- 125
11. In combination, a section of railway track, a relay for said section, a track circuit for said section including one winding of said relay, two local circuits for supplying the track rails of said section with local current of one or the other relative polarity, respectively, a second winding of said relay included in both said local circuits, and traffic controlling apparatus controlled by 60 said relay. 130
12. In combination, a section of railway track, a relay for said section, a track circuit for said section including one winding of said relay, two local circuits for supplying the track rails of said section with local current of one or the other relative polarity, respectively, a second winding of said relay included in both said local circuits, and traffic controlling apparatus controlled by 65 said relay. 90
13. In combination, a section of railway track, a plurality of local circuits for said section each including a portion of at least one rail of the section, a relay included in all said local circuits and traffic controlling means controlled by said relay. 95
14. In combination, a section of railway track, means for supplying train controlling current to the rails of said section in parallel, and a signal for said section controlled in part by said train controlling current. 100
15. In combination, a section of railway track, means for supplying train controlling current to the rails of said section in parallel, and means for giving a stop indication to a train approaching said section in the event of abnormal reduction of said train controlling current. 105
16. In combination, a section of railway track, a track circuit for said section including a source of alternating current and a track relay having a track winding and a local winding, a local circuit for said local winding including the rails of the section in multiple and a source of alternating current, and means controlled by traffic conditions in advance of said section for reversing the instantaneous relative polarity of the currents in said two circuits. 110
17. In combination, a section of railway track, a track circuit for said section including a source of alternating current and a track relay having a track winding and a local winding, and means controlled by traffic conditions in advance of said section for supplying alternating current of one instantaneous relative polarity or the other to the local winding of said relay and to the track rails of the section in multiple. 115
- 130

- 18. In combination, a section of railway track, a relay for said section having a track winding and a local winding, means for supplying alternating track circuit current to the track winding of said relay, means for supplying alternating local current to the local winding of said relay and to the rails of said section in multiple, and means governed by traffic conditions in advance of said section for reversing the instantaneous relative polarity of said currents.
19. In combination, a section of railway track, a relay for said section having two co-operating windings, means for supplying alternating current to one winding of said relay, means for supplying another alternating current to the other winding of said relay and to the rails of said section in multiple, and means governed by traffic conditions in advance of said section for reversing the instantaneous relative polarity of said currents.
20. In combination, a section of railway track, a relay for said section having two co-operating windings, means for supplying an alternating current to one winding of said relay, and means controlled by traffic conditions in advance of said section for
- supplying alternating current of one instantaneous relative polarity or the other to the other winding of said relay and to the two rails of said section in multiple.
21. In combination, a section of railway track, a relay for said section having two co-operating windings, means for supplying one alternating current to one winding of said relay, and means controlled by traffic conditions in advance of said section for supplying another alternating current to the other winding of said relay and to the rails of the section in multiple and for reversing the instantaneous relative polarity of such second current.
22. In combination, a section of railway track, means for applying an alternating difference of potential across the rails of said section, a relay having two windings one of which is connected across the rails of said section, and means for applying a second alternating difference of potential of one relative polarity or the other along the rails of said section and to the second winding of said relay.

In testimony whereof I affix my signature.

RONALD A. McCANN.
